UNITED STATES PATENT OFFICE

2,555,848

CABLE CURTAIN CONSTRUCTION

Yale W. Ehret, Elkhart, Ind., assignor to The Adlake Company, Chicago, Ill., a corporation of Illinois

Application June 23, 1947, Serial No. 756,572

10 Claims. (Cl. 160—279)

1

This invention is concerned with improvements in cable controlled shade or curtain fixtures.

It is an object of the invention to provide an improved roller curtain or shade installation particularly adapted for use in a railway passenger car or an automobile bus wherein the curtain is mounted in a window frame having opposite side guide channels which receive the ends of an apron assembly secured on the bottom of the curtain and wherein the position of the bottom of the curtain is adjustably controlled by engagement of the apron with a pair of cables, each cable having one end secured to the window frame adjacent the top of one side guide channel and the other end secured to the frame adjacent the bottom of the opposite side guide channel and each cable extending from its upper end downwardly along the adjacent side guide channel then through a longitudinal recess provided in the apron and down along the opposite side guide channel to the other end.

More particularly it is an object of the invention to provide in a curtain installation of the type described an improved curtain apron assembly which provides a more streamlined effect, which does not require endwise threading of the cables, which is provided with means for preventing endwise movement of the curtain, which is so constructed that the curtain may be cut straight at the end for attachment to the apron and which is equipped with anti-rattle means to eliminate noise in operation.

It is a further object of the invention to provide in a curtain installation of the type described a curtain apron assembly which is readily and economically manufactured from extruded metal sections, which is adapted to be quickly assembled for initial installation and disassembled for subsequent repair or replacement of parts and which is provided with hard metal bearing surfaces for engagement with the cables at the ends to eliminate undue wear on the ends of the apron.

These and other objects of the invention will be apparent from a description of the form of curtain installation which is illustrated, by way of example, in the accompanying drawings, wherein:

Fig. 1 is an elevation of a curtain installation 50 which incorporates the principles of the invention;

Fig. 2 is a section on an enlarged scale taken on the line 2—2 of Fig. 1;

Fig. 3 is a section on an enlarged scale taken 55 on the line 3—3 of Fig. 1;

2

Fig. 4 is a detail of one end of the curtain apron assembly with portions broken away;

Fig. 5 is a perspective view of one end of the curtain apron assembly;

Fig. 6 is an exploded perspective view of the end of the curtain apron assembly;

Fig. 7 is a detail view of a bottom corner of the window frame showing the bottom cable anchor; and

Fig. 8 is another detail view of the bottom cable anchor.

The form of the curtain or shade installation which is shown in the drawings comprises a curtain 10 installed in a window frame 11 which is secured in an aperture in the wall 12 of a railway car or automobile bus.

The window frame 11 comprises a bottom sill 13, a top header 14 and side frame members 15 which include oppositely disposed guide channels 16. The window frame 11 supports a conventional sash unit (not shown) on its outer side. The curtain 10 is arranged to be raised and lowered adjacent the inner side of the sash.

The curtain 10 is attached to a roller 17 (Fig. 2) which is mounted on conventional brackets (not shown) arranged in the ends of the header 14. The bottom end 18 of the curtain 10 supports a transversely arranged apron assembly 19 having its ends projecting into the oppositely disposed channels 16 and receiving a pair of cables 20 and 21.

Each of the cables 20 and 21 is attached at its upper end to opposite side guide channels 16 and each cable extends downwardly along its adjacent side guide channel to the apron 19, then through the apron 19 and down along the opposite side guide channel being attached at the bottom of the channel. With this arrangement the bottom end 18 of curtain 10 is adjusted in raised or lowered position by frictional engagement of the cables 20 and 21 with the curtain apron 19.

A top end anchor plate 22 (Fig. 2) is provided for each cable which consists of a plate portion 23 having an elongated aperture 24 for receiving a screw 25 to secure it in adjusted relation on the base 26 of the channel 16 and a cable attaching portion 27 to which the upper end of the cable is secured by clinching or the like.

A bottom end anchor plate 28 is provided for each cable (Figs. 2 and 7) which includes laterally extending stop members 29 for limiting downward movement of the curtain apron assembly 19. The stop members 29 may be conveniently formed on the top end of plate 28 by slotting the end of the plate and bending the lug members 29 out-

wardly so that they extend laterally on each side of the cable and into the path of movement of the assembly 19. The plate member 28 is secured to the channel base 26 by an attaching screw 30 and a slot 31 is provided in its lower edge for receiving the end of the cable. A member 32 is secured on the end of the cable by means of which the cable is anchored in the slot 31. The base 26 of the channel member 16 is recessed at 33 to receive the plate member 28. With this construction the apron assembly 19 may be lowered until its ends engage the stop members 29.

The curtain apron assembly 19 comprises complementary or mating inner and outer members 34 and 35, respectively, which are preferably formed from extruded aluminum sections. Apron member 34 which forms the inner portion of the assembly includes a relatively wide plate-like web portion 36, provided on its top edge with a thickened section 37 having a cut back or curved lower inner face 38 which forms one portion of a slot or recess adjacent the top of the apron assembly 19 for receiving the end 18 of the curtain 10 in clamping engagement. Apron member 34 is also provided with inwardly directed, longitudinally extending, spaced rib-like formations 39, 40, 41 and 42 intermediate its top and bottom edges, for purposes which will be described.

The apron member 35 which forms the inner portion of the apron assembly 19 includes a relatively wide plate-like web portion 43, provided at its top edge with a thickened section 44 in which there is formed a longitudinally extending curved recess 45. The lower portion of the thickened section 44 constitutes an inwardly extending rib-like formation 46 which engages the plate portion 36 of the apron member 34 immediately below the curved face 38 on the thickened section 37 of member 34, when apron members 34 and 35 are in assembled relation. The curved surfaces 38 and 45 cooperate to form a tubular recess extending the full length of the apron assembly which receives in clamping relation the end 18 of the curtain 10. The end 18 of the curtain 10 is folded back and secured over a wire rod 47 or other stiffening member, forming a beaded edge for clamping engagement in the recess.

The apron member 35 is provided with inwardly extending relatively wide rib-like formations 48 and 49. Rib 48 is spaced from rib 46 forming therewith a channel-like longitudinal recess 50, the open side of which is closed by a portion of the web 36 of the apron member 34 when the members 34 and 35 are in assembled relation. Ribs 48 and 49 are spaced from each other forming a longitudinally extending central groove or recess 51 which is adapted to receive the cables 20 and 21. The apron member 35 is provided with an inwardly extending bottom flange 52 which is adapted to cooperate with the bottom edge 53 of the apron member 34 to form a flat bottom edge or face on the assembly 19. The bottom flange 52 is spaced from rib 49 forming a longitudinal channel-like recess which accommodates ribs 41 and 42 of the apron member 34. The ribs 41 and 42 and a portion of the web 43 cooperate to form a longitudinal recess 54 adjacent the bottom of the apron assembly 19 which is the same cross section as the recess 50 adjacent the top of the assembly.

Rib formations 39 and 40 on the apron member 34 extend into the recess 51 formed between the rib formations 48 and 49 on the apron member 35. Adjacent their ends the ribs 39 and 40 are provided with pairs of spaced transverse slots

55, 56 and 57, 58, respectively, which are adapted to receive clips 59. The clips 59 are formed of a relatively hard, wear-resistant metal, such as stainless steel. Each clip 59 comprises a bent 5 over or curved end 60, relatively straight portion 61 extending from the curved end 60, a laterally offset portion 62 which is connected to the straight portion 61 by shoulder forming portion 63 and to a straight terminal end portion 64 by a 10 shoulder forming portion 65. The curved end 60 of each clip 59 is provided with a groove 66 for receiving and guiding the cable. The rib formations 39 and 40 are cut away at the ends at 67 and 68, respectively, to accommodate the curved ends 15 60 of the clips 59. The clips 59 are positioned on the rib members 39 and 40 with shoulders 63 and 65 in the laterally aligned slots 55, 57 and 56, 58. The curved ends 60 of the clips 59 extend in opposite directions and the offset portion 62 of each 20 clip 59 is positioned on the outer side of the respective rib. The straight portions 61 and 64 of clips 59 are positioned on the inside of the ribs 39 and 40 and protect the ends of ribs 39 and 40 from excessive wear due to engagement with 25 cable members 20 and 21. The clips 59 are readily assembled with the apron members and firmly retained in position in the channel or recess 51.

Apron member 34 is cut away at 69 and at 70, at 30 the top and bottom, at the end of the member. Apron section 35 is cut away in a similar manner at 71 at the top and at 72 at the bottom. The recesses formed by the cut-outs at the top and bottom of the end of the apron assembly 19 35 when the members 34 and 35 are in assembled relation are adapted to receive anti-rattle members 73 which are preferably formed of molded rubber. Each anti-rattle member 73 comprises a relatively flat head portion 74 and a stem portion 75 which extends rearwardly therefrom. The anti-rattle members 73 are secured on the apron by inserting the stem portions 75 in the ends of the recesses 50 and 54 formed adjacent the top and bottom of the apron. The head portions 74 of the anti-rattle member 73 extend beyond the outer lateral faces of the apron assembly 19 and prevent metal to metal engagement of members 34 and 35 with the side guide channels 16. The head portions 74 are sufficiently thick to extend 45 beyond the ends of the apron assembly 19 approximately on a line with the ends of the clip members 59 so that they separate the ends of the apron assembly 19 from the base 26 of the channel 16, allowing only sufficient room for the movement of the cables 20 and 21. In this manner excessive endwise shifting of the apron assembly 19 and the curtain 10 is prevented.

The apron members 34 and 35 may be secured in assembled relation by means of screws 76 50 spaced along the length thereof which extend through holes provided in the web portion 36 of member 34 and engage in threaded engagement in mating holes provided in rib formations 48 and 49 of member 35.

55 While the invention has been disclosed as particularly adapted for use in railway passenger cars or buses, it will be understood that its application is not limited to such installations. It 60 may be employed wherever a retractable curtain or shade is used to cover an opening and it is desired to be able to readily raise and lower the bottom of the curtain or shade. The details of construction which are shown and the materials referred to are intended as examples only. Other details of construction and other materials may 70

be resorted to within the spirit of the invention.

I claim:

1. In a fixture adapted for association with the movable end of a cable controlled shade, complementary readily separable plate-like front and back members having inwardly directed spacer members providing a passageway between said front and back members when they are in assembled relation, said passageway accommodating the controlling cables for said shade, and end 10 guide members having hard metal end bearing surfaces, said guide members being secured to said spacer members adjacent the ends of said passageway for engagement by said cables as said cables emerge from said passageway, said cables passing around and by said guide members in opposite vertical directions.

2. In a shade fixture adapted for association with the end of a shade, complementary separable plate-like members having spaced inwardly directed longitudinal rib members forming internal passageways between said plate members when they are positioned in assembled relation, one of said passageways accommodating the cables for said shade and hard metal guide members secured in the ends of said passageway having curved ends with which the cables engage as they emerge from the fixture.

3. In a shade fixture adapted for association with the end of a shade, complementary separable plate-like members having spaced inwardly directed longitudinal rib members forming internal passageways between said plate members when they are positioned in assembled relation, one of said passageways accommodating the cables for said shade, and hard metal guide members secured on the ends of said rib members forming said passageway, said guide members having curved ends with which the cables engage as they emerge from the fixture.

4. In a fixture adapted for association with the movable end of a cable controlled shade, complementary plate members secured together in spaced relation, said plate members having longitudinal rib formations which define a passageway between said plates for receiving the cables for said shade, said rib formations being cut away at their ends and having a pair of aligned transverse slots spaced from said ends, hard metal guide members for said cables, each having a curved end and a relatively straight end, said guide members each having portions on said straight end interengageable with said transverse slots to detachably secure the same to the ends of said rib formations, the curved ends of said guides providing curved bearing surfaces for said cables as they emerge from said fixture.

5. In a fixture adapted for association with the movable end of a cable controlled shade, complementary plate members adapted to be secured together in spaced relation, said plate members having longitudinal rib formations which define passageways between said plates, one of said passageways receiving the cables for said shade, said rib formations being cut away at the ends of said passageway and provided with a pair of aligned transverse slots spaced from said ends, hard metal guide members for said cables, each having a curved end and a relatively straight end, said guides each having portions on said straight end interengageable with said transverse slots to detachably secure the same to the ends of said rib formations, the curved ends of said guides providing curved bearing surfaces for said cables

as they emerge from said fixture and another of said passageways adjacent the top of said plate members receiving an end of said shade in clamping engagement.

5. In a cable controlled shade construction, a bead formation on the movable end of the shade, a fixture comprising complementary front and back members having inwardly directed rib-like members providing a plurality of passageways between said front and back members when they are in assembled relation, the uppermost one of said passageways receiving said bead formation to clamp said fixture to said curtain, another one of said passageways accommodating the controlling cables for said shade, and end guide members positioned adjacent the ends of said passageway for engagement by said cables as they emerge from said passageway and pass in opposite vertical directions, each of said guide members having a hard metal end bearing surface.

7. In a shade fixture adapted for association with the movable end of a cable controlled shade, complementary members having inwardly directed longitudinally extending means defining a plurality of longitudinally directed recesses in said fixture when said members are in assembled relation, the top one of said recesses being adapted to engage in clamping relation the end of the shade and an intermediate one of said recesses 25 accommodating the controlling cables for said shade, and rubber-like anti-rattle members having portions received in the ends of other longitudinal recesses in said fixture.

8. In a shade fixture adapted for association with the movable end of a cable controlled shade, complementary members having inwardly directed longitudinally extending members defining a plurality of longitudinally directed vertically aligned recesses in said fixture when said members are in assembled relation, the uppermost one of said recesses being provided to engage in clamping relation the end of the shade and an intermediate one of said recesses being provided to accommodate the controlling cables for said curtain, and rubber-like anti-rattle members having head portions and stem portions, said members being cut away at the top and bottom of the ends thereof to accommodate the head portions of said anti-rattle members, the stem portions of 50 said anti-rattle members being received in the ends of an upper longitudinal recess and a lowermost longitudinal recess in said fixture, respectively.

9. In a window construction of the type having a roller mounted shade with a cable engaging fixture on an end thereof which fixture extends transversely between the side guide channels and a pair of cables each of which is secured at its upper end in the upper portion of a side guide channel and at its lower end in a recess in the lower portion of the opposite side guide channel, a combination fixture stop and cable end anchoring means comprising an anchor plate secured in one of said recesses provided in the lower portion 60 of the guide channel, stop members for said fixture extending laterally from said anchor plate, said anchor plate being provided with a slot adjacent its lower end for receiving the cable, and an abutment member on the end of the cable to anchor the same in said slot.

10. In a window shade construction for installation in a window frame having side guide channels, said shade construction being of the type having a roller mounted shade with a cable engaging fixture on the end thereof and a pair of

cables each of which is secured at its upper end in the upper portion of a side guide channel and at its lower end in the lower portion of the opposite side guide channel, said guide channels being provided with a recess adjacent the lower end, means for anchoring the lower end of each cable comprising an angle plate having one leg secured in the recess adjacent the bottom end of the guide channel and the other leg thereof extending inwardly of the window frame, said angle plate being provided with an inwardly directed slot in the lower end of the leg which is positioned in said recess for receiving the cable, and an abutment member on the end of the cable to anchor the same in said slot.
